AUTOMATIC TICKET CASH REGISTER

Peter Zulinski, Astoria, and Philip Fleischman,
Bronx, N. Y.

Application October 2, 1931, Serial No. 566,404

3 Claims. (Cl. 235—58)

This invention relates to registering devices, and has particular reference to cash registers, and methods that may be practised in association therewith.

5 One object of the invention is to provide a device of the character described having improved means which are responsive to the perforations or marks in an article so as to operate or register according to the maximum amount 10 or value of such perforations, in accord with the different or successive positions of the several perforations.

Another object of the invention is to furnish a device of the nature set forth having improved 15 means coacting with an article, such as a check, in such manner that the means may be adjusted for different periods of time or circumstance so as to coact with only such articles or checks as are proper for any particular period of time.

20 Another object of the invention is to construct a device of the class alluded to having improved means for registering the maximum amount punched on a member and for operating a suitable counter mechanism; another object of the 25 device is to provide improved means automatically responsive to the maximum amount indicated on a member and to display said amount on an indicia bearing member; another object is to provide improved means for operating a counter mechanism and an indicia bearing 30 means which is adapted successively to show the separate amounts additively recorded by the counter mechanism.

Another object of the invention is the provision 35 of an improved device of the type mentioned wherein a means responsive to the amounts shown on a check or the like is operative only after operation of another means which is responsive to a time indicia or the like borne by the check.

Another object is to provide an improved mechanical method of registering, checking or indicating, to minimize inaccuracy, save time and labor and prevent fraud.

45 Another object of the invention is to provide improved means for each of the following purposes, singly or in any combination: means for guiding and holding a paper or flexible check; means whereby a nonconducting check element causes an electrical circuit to be closed 50 for energizing a registering or indicating device; means whereby contact pins are successively projected against a check; means whereby a rotary device will operate all of said pins during a single rotation of the device; means whereby actuation of the pins is caused by fingers one of which makes contact through a properly positioned opening in a check, which position may be changed from day to day; an arrangement 55 whereby the preceding means may be readily

adjusted; means whereby a counter is operated on the instant that the first pin makes electrical contact; means including toothed clutches for aiding in the accurate synchronization of the mechanism; means for automatically ejecting a 5 check after the registering operation is completed; means whereby a single rotary device may actuate a counter or indicator on rotation in one direction, and the ejecting means on rotation in reverse direction; an improved two way 10 clutch means for the preceding means; means whereby a display indicator or the like is operated only according to the amount of the check and then returned to zero position; means including solenoids for operating the registering or 15 indicating mechanism; means whereby a drawer or other element may be automatically unlocked and locked before and after the registering operation, respectively; means whereby opening of the drawer or other receptacle operates a switch 20 to break the line circuit to the mechanism; means for controlling or regulating the passing of people before the machine; means whereby the register or indicator operates the preceding means as the operation of the machine begins or 25 is completed; means for indicating when the machine is to be emptied of its checks, and numerous associated or correlated mechanisms, elements, supporting means.

A further object of the invention is to provide 30 a machine of the nature set forth which shall have comparatively few and simple parts, which shall be inexpensive to manufacture and assemble, quick and easy to operate; reliable, rugged, and efficient in use.

35 Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawings, wherein like parts are designated by the same reference characters throughout the 45 several views.

In the drawings:

Figure 1 is a vertical sectional view of a device embodying the invention, taken on the line 1—1 of Fig. 2, and with a part removed.

Fig. 2 is a view in vertical section taken on the line 2—2 of Fig. 1, and with a part removed.

Fig. 3 is a view in horizontal section taken on the broken line 3—3 of Fig. 2, and with a 55 part removed.

Fig. 4 is an enlarged fragmentary vertical sectional view taken on line 4—4 of Fig. 1.

Fig. 5 is a view in elevation, with parts in section, of a rotary stop device.

- Fig. 6 is a vertical sectional view of the two way clutch.
- Fig. 7 is a view in horizontal section taken on the line 7—7 of Fig. 1.
- 5 Fig. 8 is a transverse sectional view taken on line 8—8 of Fig. 7.
- Fig. 9 is a plan view of a check.
- Fig. 10 is an energized view in elevation of the two way clutch.
- 10 Fig. 11 is a fragmentary enlarged vertical sectional view of a drawer operated switch.
- Fig. 12 is a fragmentary diagrammatic view of a cam arrangement for successively actuating the contact pin levers.
- 15 The advantages of the invention as here outlined are best realized when all of its features and instrumentalities are combined in one and the same structure, but, useful devices may be produced embodying less than the whole.
- 20 It will be obvious to those skilled in the art to which this invention appertains, that the same may be incorporated in several different constructions. The accompanying drawings, therefore, is submitted merely as showing the pre-25 fered exemplification of the invention.
- Generally described, this invention provides a device and method of checking, registering or indicating amounts or values of articles, services, or purchases of any kind, and it may be best 30 illustrated in connection with a check which is used in cafeterias and which is punched every-time that a purchase is made. Heretofore it has been possible for employees to substitute other checks having punch marks of lesser amount and 35 to ring up such lesser amount on the cash register. Hence owners of cafeterias have sustained a considerable and continuous loss. By this invention, the check is handed to the cashier by the customer, and the cashier inserts the check into the 40 machine. The machine thereupon operates an indicator which shows the total amount of the check, and the customer may be guided by such indication and pay the amount thus shown. Furthermore, this amount is shown by a counter, so 45 that the receipts may be accurately checked. The checks are received and retained in the machine, to be removed therefrom only by the owner or other authorized person, thus precluding the possibility of substitution of checks.
- 50 Moreover, to prevent fraudulent preparation of checks in advance, all the checks issued on any one day may be differentiated from those issued on a preceding or other day, by a mark which may be printed, but is preferably in the nature of 55 a notch, which may be placed, for instance, on the edge of the checks, by the management without the knowledge of the cashier or other employees. The machine is likewise adjusted, and will respond to the check only if the notch there-60 in is in proper position on the check. The cash register is intended to be closed and is automatically locked after each transaction, but on inserting a check, the machine begins to operate and the cash drawer opens. To regulate the 65 passing of customers before the machine in process of paying their checks, an automatic control may be used which is operated on opening or closing of the cash drawer. In the drawings has been shown a full and complete embodiment of 70 the invention to comply with the patent statutes, but the same is to be considered as merely illustrative of one possible form of the invention.
- The term "check" as used herein is intended 75 to denote any article or device, of any size, shape or function which may operate by reason of its size or other quality, as well as the perforations herein shown. Similarly the term "cash register" or the like, is to be broadly construed for any type of value, amount, speed or quantity recording or indicating device; and all terms herein used are to be correspondingly read and understood, separately and in their various relations, in the same broad and comprehensive sense. 5
- Referring in detail to the drawings, 10 denotes a device embodying the invention. The same 10 includes a casing including a main casing section 11, a drawer casing section 12 therebeneath, and a base casing section 13. Disposed upon the main section 11 is an indicator casing section 14. 15 denotes the front wall of the main section, and 16 a window through which may be observed the amount registered by the device. It will be clear that the entire casing structure may be made of any suitable material, in one or more parts, and of any suitable form to accommodate the invention. 20
- Formed in an upper portion of the casing section 11 is a check receiving guide or slot 17 with which registers a suitable guideway 18 for the check. This guideway may be formed between 25 a pair of rigid members 19, 20 which may be mounted upon the casing. The said members 19 and 20 may be secured to a wall or bracket structure extending parallelly to the front wall 15 and including a central offset upward extending housing portion 20a and having oppositely extending bars 20b and 20c secured to the side walls of the main casing. To guide the check lengthwise into the guideway 18 along a wall 19 thereof, a pressure means such as a plurality of resilient or 30 wire members 21 may be provided extending in substantial parallelism along the guideway and in proximity to said wall. These wire members may be secured to the wall 20 at 22 and 23. Beyond the lower end of the wall 19, the members 40 21 may each have a curved cam portion 24 for guiding the check from the guideway. Thus it is seen that after the check has been fully inserted into the guideway, it may be maintained at rest for a suitable time interval by means such as the 45 members 21, both of which bear on the check, the latter being thereafter readily moved onward along the cams 24, as hereinafter described. 50
- The check 25 may be of any suitable shape or construction. The form illustrated shows a well known type of check, to which, however, the invention is not limited, as it may also include any various types of tickets or tokens, depending upon the specific construction of the machine and the use to which it is put. The check 25 may be 55 made of a stiff paper, fabric, or other material in which openings or deformations may be made by a suitable tool. Preferably paper of a substantially water proof nature, is desirable. The check 25 may have one or more rows or columns 60 26, 27 of suitable spaces or indicia, such as 28, arranged in a predetermined manner, so as to increase in regular or predetermined amounts in a given direction. For instance, the amounts may increase from 5 cents at one end of the 65 check to 50 cents at the opposite end, and then in reverse direction, from 55 cents to \$1.00 along the other column of the check. However, any amounts may be used, and reference may be had, as in factory use, to the numbers of articles 70 produced, the amount or value of work done, matters of speed or time, and generally to any kind of device, system or process which is capable of measurement in an accurate or arbitrary manner. 75

The check 25 may be punched as at 29, 30 and 31 after each measurement or scale, and the check indicates a total purchase of 75 cents.

In order to permit a given check to be used only 5 on a specified day, or time interval, or condition, the check may have a supplemental deformation or marking, as, for example, a notch 32 in an edge thereof. Thus all the checks to be used for one day, may have the notch located in the 10 same position, while, on the following day, checks having notches in a different position will be used. The notch, which may be disposed in spaced relation to the indicia 28, so co-operates with a device mounted on a shaft 40, which is 15 correspondingly preset, all as hereinafter described that only a properly notched check will cause the operation of the device. In this manner, the management of a cafeteria, or other establishment can control the checks used so as to 20 prevent fraudulent use of checks by employees to defeat the objects of the machine.

Now, when the check 25, with the amounts punched thereon, is inserted into the guideway 18, preferably by the operator of the machine, the 25 latter registers the amount and suitably operates the cash register to control the opening thereof. But if the notch 32 is in improper position on the check, the machine and cash register will be prevented from operating by a means that 30 will now be described.

As shown in Fig. 3, the guideway 18 has a lateral longitudinal extension 33 in which is mounted a suitable means responsive to the notch 32. One form of construction, includes a plurality of horizontally extending, vertically spaced fingers 34, preferably seven in number to correspond to the days of the week. These fingers may be mounted for actuation in any feasible manner, as by loosely pivoting on a pin 35 and 40 spaced from each other by suitable spacers 36 on the pin. Preferably the pin 35 passes through slots in the fingers, as shown. Each finger may be individually operated by a leaf spring 31, so as to move away from the buss bar 38 which is 45 mounted on the wall 19. Coacting separately with the fingers 34, are provided a plurality of equally angularly spaced cams 39 fixed upon a shaft 40, in the planes of the corresponding fingers. This shaft is journaled at its upper end 50 41 in the top of the casing, and has rigidly secured to its lower end a supplemental alined shaft 42 which is journaled in a bearing 43 at the bottom of the main casing 11. Journaled on the shaft are a pair of collars 44 and 45, the former 55 of which is slideable along the shaft and is held against relative rotation thereto by a pin and slot connection 46, 47. The shaft 42 is rotatable relatively to the collar 45, and both of the collars have releasable toothed engagement at 48. An 60 expansion coil spring 49 acting between the abutment 50 and the collar 44 tends to drive said collars into engagement. For manually turning the shaft 42 through an angle corresponding to an angle of a cam 39, so as to bring a different 65 cam 39 into operative relation to a finger 34, the shaft has a suitable head 51 at its upper end engageable by a tool. When a torque is applied to the shaft, the collar 45 being normally held against rotation except as hereinafter described, 70 the teeth 48 cause the collar 44 to move upward against the force of the spring 49, for re-engagement of the teeth in a different angular position. In operation, as will be more particularly described hereinafter, the selected cam is in operative 75 engagement with its corresponding contact

39 as shown in Fig. 3, the cam being oscillated first counterclockwise and then clockwise so as to be restored by the latter movement to initial selected position automatically, this operation being the same for all similar tickets and notches 25, 32. 5

When the check 25 is inserted into the guideway 18, the check causes actuation of a suitable means, electrical or mechanical, for operating the cams 39. For instance, the end portion of the check presses laterally against a lug 52 of a bell crank lever 53 that is pivoted at 54 on a bracket 54a secured to the wall member 19. This lever carries a contact plate 55 which is removably retained thereon by a leaf spring 56. Another contact 57 is carried by a screw 58 that is threaded through an arm 59 of the bracket 54a, and is rotatable by a knob 60 for adjusting the gap between the contacts. An expansion coil spring 61 normally keeps said contacts apart, but, on insertion of a check, the bell crank lever is swung 20 clockwise and the contacts engage.

Electrically coacting with said contacts 55, 57 are wires 62, 63 connected to the bell crank lever 53 and a bus bar 64, and to the bracket 54a and a solenoid 65 respectively. (See Figs. 3 and 4.) 25 Another wire 66 is connected at one end to a buss bar 67 and at its opposite end to solenoid 65. The buss bar 67 may be connected to a conventional electrical line socket 68 by a conductor 69, and the buss bar 64 is connected to 30 a fuse 70, and hence through a cash drawer switch device hereinafter described, to the socket 68. Thus the solenoid 65 is connected in circuit and energized. This solenoid has a core 65a connected by a link 71 to an arm 72 extending 35 laterally from the collar 45. Opposing the movement of the solenoid, is a tension spring 73 secured to said arm and to a fixed post 74. When the solenoid is energized, a counterclockwise movement of the shaft 40 is caused, with a corresponding rotation through a suitable angle of 40 all the cams 39, through the angle of one cam 39, for actuating one of the fingers 34. If the notch 32 is in proper position on the check, the free end of the actuated finger 34 passes through 45 the notch and contacts the buss bar 38. This causes operation of a suitable means that is responsive to the punched holes in the check as will now be described. If there is no notch at the actuated finger, the same yields so as to 50 prevent cutting of the check.

Connected electrically to the buss bar 64 as by a wire 75, is a solenoid 76. Another wire 77 runs from said solenoid to the buss bar 38. To complete the circuit, a third wire 78 is connected 55 to the buss bar 67 and to a conductor rod 79 having at its free end a grooved portion 80 for sliding electrical engagement with the shaft 40. (See Figs. 3 and 4.) In this way, if any one of the fingers 34 touches the buss bar 38, the solenoid 76 is energized, with the current flowing 60 through the shaft 40, a cam 39, and a finger 34.

The solenoid 76 is provided with a movable core 81 connected by a link 82 with a lever 83 that is pivoted on a shaft 84 journaled in a fixed 65 bracket 85. Opposing the action of the solenoid is a tension coil spring 86 connected to the lever and to a stationary post 87. Also connected to the lever is a reciprocating rack bar 88, the teeth 89 of which mesh with the teeth of a pinion 90 70 that is mounted on a shaft 91. To provide for a small degree of oscillation of the rack bar, while retaining the same in uniform engagement with the pinion, a yoke 92 is pivotally mounted on the shaft 91 so as to engage around the back 75

of the rack bar. The shaft 91 is journaled in lugs 93 of the bracket arm 20b, in a bracket 94 secured to said bracket arm, and also in the spaced angular plates or lugs 95 which are at the inner ends of the bracket arms 20b and 20c. Between said lugs is a wall member 96 disposed in the plane of the member 20 but positioned therebeneath. Fixed on the shaft 91 between said lugs, are a plurality of spaced cams 97, preferably twenty in number to correspond to the number of indicia marks on the check 25. Each of these cams has a recess 98 in the face thereof, the recesses for all the cams including portions uniformly angularly spaced through an angle of approximately 360 degrees. Thus said portions are formed by recesses which successively increase by equal angles, the first of these recesses being shown in the drawings. In general, the arrangement of the cams is such that the levers are successively actuated and maintained in actuated positions during the successive movements, as hereinafter described. Coacting with the different cams respectively are levers 99 having follower portions 100 disposed along a common plane. All of the levers may be pivoted on a common shaft 101, and they may all be pressed toward the cams by a common leaf spring 102. The levers are spaced for accurate alinement with their corresponding cams, the latter being similarly spaced by means of discs 103 which are substantially larger in diameter than the cams so as to guidingly receive the levers therebetween. Connected to the upper ends of the levers are a plurality of contact pins 104 which may be arranged above one another in two parallel rows 104a and 104b. These pins are suitably slidingly guided in parallel holes 105 in the wall member 20 which may be made of insulating material. The spacing and arrangement of the pins 104 is such as to accurately correspond to the indicia on the check 25. For convenience in construction, the pins vary in length gradually, the uppermost pins being longest. The levers 99 are pivotally connected to the pins at 106, and all the levers for one row of the pins have their upper portions 99a in a common plane, in alinement with the plane of the pins. At 99b, the levers are laterally offset and extended straight downward so as to lie in spaced side by side relation, and at 99c, the levers are formed so as to extend inward toward the wall member 20, and then downward but along a common line at 99d so as to extend in a vertical direction to the shaft 101. The construction and arrangement of levers 99 is clearly shown in side elevation in Fig. 4, and in edge elevation in Fig. 1. Said levers may be variously arranged and shaped so as to clear each other and to lie compactly side by side; these forming no feature of the invention.

It will now be understood that when the solenoid 76 is energized, the rack bar 88 is moved downward sufficiently to cause a substantially complete rotation of the cams 97. As such rotation progresses, the cams cause successive actuation of the levers 99 and a corresponding tendency of the pins to successively move through any punched holes in the check 25. As will be noted, the pins have reduced ends for easy entrance into the holes in the check 25. At those places in the check where there are no holes, the movement of the pins is arrested by the check, and the levers 99 for said pins have sufficient resilience to adequately spring for accommodation.

In practice it is preferred that the cams 97

be so arranged as to cause the movements of the pins to follow the order to the indicia on the check beginning from the maximum amount. Consequently the pin corresponding to \$1.00 will be first actuated, and that pin which corresponds to 5 cents will be last actuated. Owing to the conformation of the successive cams, which have dwells of decreasing sizes and recesses of increasing size each lever 99 which is actuated will remain in operated condition until the rotation of the cams has been fully completed. When that has been accomplished, the followers 100 of the levers reseat in their respective cam recesses so as to cause release of the levers 99 and the pins 104 thus, in turn, disengaging the check in the guideway 18.

Coacting respectively with both rows of pins 104a and 104b, are a plurality of buss bars 107 and 108. These are interconnected back of the wall 19 by a conductor plate 109 having a binding post 110. To the latter is engaged a wire 111 which is connected to the buss bar 64. A brush 112 is mounted to wipe against a clutch casing 113 hereinafter described. This brush is connected by a conductor 114 with a solenoid 115, from which extends another conductor 116 to the buss bar 67 to complete the circuit. The circuit is completed by contact of pins 104 with buss bars 107, 108, and through levers 99 carrying the pins, and through shaft 91b carrying the levers and the clutch 113, and hence to the brush 112. The solenoid 115 may be used to operate a counter mechanism as will be described subsequently. It will be appreciated that suitable insulation may be used wherever required to prevent short circuiting, and the positive end of the line may be connected preferably to the buss bars 107 and 108 rather than to the contact pins 104. In any case it will be clear that the current may flow through the shaft 91 and the levers 99 and pins 104 to the buss bars 107, 108 with which the pins may contact through the holes in the check.

It may now be understood that, by this arrangement, and as will be more specifically described hereinafter, the device is well adapted to register the punch mark corresponding to the maximum amount punched on the check. As soon as such maximum punch mark is penetrated by a pin 104, the circuit is closed to the solenoid 115 and certain operations are initiated, according to which any subsequent penetration of other punch marks on the check by other pins 104 will be immaterial to the accurate operation of the machine.

The invention may include a counting mechanism, and if the same is connected for operation by the shaft 91, it may be desirable that the latter shall not rotate in reverse direction, which would happen when the solenoid 76 is de-energized and the spring 86 retracts the rack bar 88 and causes reverse rotation of the pinion 90. Accordingly, a clutch 117, (see Fig. 6) may be interposed in the shaft 91 between the sections 91a and 91b thereof. This clutch may be in the nature of a two way clutch and include the casing 113 consisting of opposite end wall members 118, 119, the former of which rotates in an opposite direction to the latter, and an intermediate circular portion 120. The latter includes a hub 120a on a wall 120b, which hub is keyed to the shaft section 91a at 120c, and is provided with angularly spaced radial inwardly extending lugs 121, one adjacent to each wall 118, 119. On these lugs are pivotally mounted the dogs 122, 123.

which extend into the end walls 118, 119, the latter being each of channel form in cross section. A pin 124 is fixed to the wall 120b of the intermediate member 120, and on this pin is mounted a spring 125, the central portion of which is coiled around the pin and the end portions of which bear on the dogs so as to tend to throw them simultaneously outward. Each of the end walls 118, 119 has a recess 122a and 123a for its corresponding dog. Consequently, when the solenoid 76 is energized, the dog 123 is operative to cause rotation of the intermediate shaft section 91b, while the dog 122 is idle and hence the wall 118 of the clutch may be stationary for a purpose later stated. But when the solenoid 76 is de-energized, and spring 86 causes reverse rotation of the shaft section 91a, the dog 123 is idle, and the dog 122 operative to rotate the member 118. It will be noted that due to the arrangement of the clutch the angular rotation of members 118 and 119 is approximately equal.

A counting device may be provided which may include a continuous counter, and a counting mechanism that is reset to zero for each day. Such counting mechanisms are well known and the principles thereof are illustrated in U. S. Patents Nos. 950,645, issued March 1st, 1910; 1,044,-710, issued November 19th, 1912; 1,521,137, issued December 30th, 1924; and many other patents such as those issued to The Veeder Manufacturing Company, of Hartford, Connecticut, U. S. A. The counting device may include separate interconnected counters each of which may register up to different maximum amounts. To illustrate the device, it will suffice to show a plurality of counters 126, 127 and 128 which may be suitably geared together at 129. To drive the counters, a third section 91c may be provided for the shaft 91. Interconnecting the sections 91b and 91c may be arranged a clutch 130 consisting of two disc elements having mating teeth, which are preferably twenty in number for each of them to correspond to the number of indicia on the check 25. This clutch is normally retained open by a yoke 131 carried by a lever 132 pivoted on a fixed pivot 133 on the bracket arm 20c; this lever being actuated by an expansion coil spring 134 which acts at one end on an arm 135 of the lever, and at its other end on a bar 136 affixed to said bracket arm. The solenoid 115 has a plunger 137 connected by a link with the free end 138 of the lever 132, so that when the solenoid is energized, the clutch 130 is closed.

Since the solenoid 115 is energized on the instant that a pin 104 makes contact through a maximum perforation in the check 25, the operation of the counters will instantly begin and will continue to the low value end of the check, the cams 97 being arranged for successive operation of one row of the pins 104 in an upward direction from 100 to 55 on the check and then of the second row of pins 104 in a downward direction from 55 to 5. If the value of the check is 65, the counter is rotated through 13 units of angle, and if the value is 15, the counter is rotated through 3 units of angle. Thus the counters will register the full maximum amount of the check. By providing twenty teeth in the clutch 130, any slight lost motion in the mechanism is automatically corrected when the clutch is engaged, assuring proper synchronism in the operation.

To assure against any accidental reverse rotation of the counters, a ratchet wheel 139 may be mounted on a hub 140 of one of the clutch ele-

ments 130 that is secured to shaft section 91c. With the teeth of this ratchet wheel may coact a suitable fixed leaf spring 141.

A suitable display indicator may be provided to show through the window 16 the amount of the check registered by the machine. For this purpose a disc 142, for instance, may be provided, which may carry indicia corresponding to the indicia on the check 25. Such indicia may be arranged along a circle or arc of any suitable angle. The disc may be mounted on a hub 143 of a bevel gear 144 that is journaled on a stationary shaft 145 secured to a bracket arm 145a that extends from a long upright bracket 145b. The latter may be fixed to the casing and wall 19 by bolts 145c and 145d. Engaging this bevel gear is a second bevel gear 146 that is freely journaled on an end of the bracket arm 145a (see Fig. 3). Fixed to a shaft 147 which is journaled in a bracket 147a secured to the wall 19, is a sprocket wheel 148 connected by a chain drive 149 over the idlers 150 and extending thence downward around a sprocket wheel 151 secured to the main shaft section 91c. The idlers 150 may be journaled on stub shafts 152 fixed to the vertical frame bar 136.

As it is desirable that the disc 142 shall return to zero position for each check inserted into the machine, a clutch 153 may be arranged to connect the bevel gear 146 with the shaft 147 when the clutch 153 is closed. When this occurs, the disc 142 will rotate in precisely equal angles with the shaft section 91c for the counters. The clutch includes one member fixed to said bevel gear, and other member splined to the shaft 147 and slideable therealong by conventional means such as a guide member 154 and yoke 155. The latter is pivotally mounted at 156 on a suitable bracket arm 156a which may be part of the large bracket 145b. It is intended that the yoke shall be moved toward the left by any feasible means to open the clutch 153 when the operation of the counters and display indicator disc 142 has been completed, and such means may be provided in connection with the check ejecting means hereinafter described. In any case, when the clutch 153 is opened, the disc 142 may be returned to zero position by a torsion coil spring 157 which is wound around the stationary shaft 145 and secured thereto at one end, and at its other end at 158 to a cam shaped plate 159 that is fixed to the hub 143. Also fixed to said shaft 145 at 160 is a resilient stationary member 161, the end 162 of which is adapted to ride along the edge 163 of the cam 159 so as to engage in the notch 164 to act as a positive stop for limiting the return movement of the display disc 142 under the action of the spring 157.

After operation of the counters and disc 142, the check 25 is automatically ejected from the guideway 18 by suitable means, one form of which will now be described. Any drive means that may be used for the purpose, may include a sprocket wheel 165 fixed to the member 118 of the casing 113 of the two way clutch 117. A chain 166 which may be straight or crossed as may be necessary, passes through an opening 167 in the bracket wall 20b and connects the sprocket wheel 165 with a sprocket wheel 168 that is mounted on a shaft 169 journaled in the bracket 145b. Mounted on the shaft is a second sprocket wheel 170 which is connected with a chain to a sprocket wheel 171 on a shaft 172 journaled in a bracket arm 145e of the bracket 145b, so that the shaft 172 is above the shaft 169 and extends in parallel

relation thereto. Fixed on each of the shafts 169 and 172 are rollers 173 and 174 respectively which may be made of a suitable frictional material such as rubber. See Fig. 4. These rollers 5 are disposed in the same vertical plane. The upper roller 174 communicates at right angles with the guideway 18 through a slot 175 in the wall 19, between the buss bars 107, 108 and in alignment with the wire springs 21, so that the check 25 may be gripped between the roller 174 and said springs. To facilitate insertion of the check 25 into the guideway 18, the roller 174 10 may have a plane edge portion 176 for clearance. The lower ejecting roller 173 is positioned with 15 an edge thereof in close proximity to the cam portions of the springs 21.

When the main shaft section 91a reverses under the action of the spring 86, the sprocket wheel 165 is turned in a corresponding direction, and causes 20 rotation of the shafts 169 and 172, and hence of the rollers 173, 174, in the clockwise direction. The upper roller 174 feeds the check 25 downward along the springs 21 to the lower roller 173, which discharges the check into a suitable receptacle 177. Obviously the circumferences of 25 the rollers 173, 174 may be made sufficient to completely eject a check with a single rotation of the rollers. The upper roller 174 is now again in its initial position with the plane portion 176 30 disposed toward the guideway 18 which is thus ready to receive another check.

It will be noted that when the check 25 is completely ejected the bell crank lever 53 is free to swing counterclockwise to break the contact at 35 55, 57, causing release of the solenoid 65.

To operate the yoke 155, a disc 178 is mounted on the shaft 172, this disc carrying a cam element 179 near its periphery. This cam element 179 is adapted to strike a pin 180 fixed to the yoke 40 so as to cause the same to move into open position, an action which is accomplished as the ejection of the check 25 is completed. Thereupon the spring 157 reversely rotates the disc 142 to initial position, as hereinbefore described.

45 To close the clutch 153, an arm 181 extends from the collar 45, see Fig. 2, this arm having pivotal connection 182 at its end with a lever 183. The latter has an intermediate pivot at 184 on an arm 145f of the bracket 145b. At its 50 other end, the lever 183 has a rule break joint at 185 with the arm 186 of the yoke 155 below the pivot 156. For this purpose the arm 186 may have a channel portion 187 at its lower end for receiving the lever 183. Now, when the solenoid 55 65 operates, this being the first solenoid to be energized, the lever 183 is caused to swing clockwise. This causes the yoke arm 186 to swing counterclockwise, so that the clutch 153 is closed, the rule break joint 185 being effective. But said 60 joint will permit the yoke to be moved in reverse direction to freely open the clutch 153 by means of the cam 179.

It may now be noted that the invention embodies a principle that all the essential rotating 65 parts thereof function by a rotation not in excess of 360° C. In this manner accuracy and simplicity in a high degree is obtained.

To give the operator of the cash register suitable notice that a predetermined number of checks 70 have been received in the receptacle 177 so that the same will be emptied, we may provide a slide 188, or the like which is guided on the members 189 for movement transversely to the mouth of the guideway 18. A suitable speed reduction 75 means may be used, including a small suitably

mounted roller 190 frictionally engaging the roller 174 and another roller 191. The latter may be mounted on a shaft 192 journaled on the ears 193 of the guides 189. Rotatably mounted on said shaft 192 is a finger 194 which is engageable with a lug 195 of the slide so as to tend to move the same into closing position. A torsional coil spring 196 is connected to said shaft 192 and to the finger 194 so as to resiliently move the finger as stated. A tension coil spring 197 tends to move the slide to open position. As the roller 174 rotates the roller 191 is slowly turned and after a great number of checks 25 have been received, the finger 194 is gradually caused to close the slot 17. However, the slot is of sufficient width to still permit reception of checks. But the receptacle 177 10 may now be emptied, and the operator may engage the lip 198 on the slide to draw the same toward the right, thus permitting the finger 194 under actuation of the spring 196, to quickly pass 15 the lug 195. The lip 198 is then released, and the spring 197 retracts the slide to open position.

The receptacle 177 may be supported in the main casing section 11 on inclined guides or supports 199 mounted on the bottom of said section 25 at 199a and 199b. For removal of the receptacle 177, a door 200 may be provided at the rear of the main casing, this door being hinged at 200a and locked at 201. A handle 202 on said receptacle facilitates removal thereof. The rear 30 wall 203 may be re-enforcingly connected to the bracket 204 by means including a bracket 204.

The drawer casing 12 is separated from the main casing by a horizontal wall 205 which may afford support to various members and brackets 35 in the main casing 11. A similar wall 206 separates the base casing 13 from the drawer casing. In the casing section 12 may be provided a conventional cash drawer 207 having partitions 208 and 209 providing a plurality of compartments. 40 This drawer may have the grooved guide members 210 which are adapted to ride on the anti-friction rollers 211 mounted in the wall 206.

It is preferred that the drawer 207 shall always be closed and locked after payment has been received from a customer, said drawer to be released only on the full insertion of a check 25 in the guideway 18. Accordingly a lever 212 (see Fig. 2) is pivotally mounted at 213 between a pair of brackets 214, secured to the wall 205, (see Fig. 50 1). This lever is normally urged in counterclockwise direction by a compression coil spring 215. The lever is provided with a toe 216 which is engageable by a finger 217 fixed to the shaft 84. At its other end, the lever is provided with a locking head 218 which is adapted to pass through an opening 219 in the wall 205 for engagement with the rear wall 220 of the drawer 207 to prevent the opening of the drawer.

When the solenoid 76 is energized, the shaft 84 60 is rocked, causing the finger 217 to swing the lever 212 in clockwise direction, elevating the locking head 218 to release the drawer. When the solenoid 76 is de-energized, and the drawer is moved into closing position, the locking head, 65 due to the inclination of the lower edge 221 thereof, rides easily over said wall 220 and locks therewith.

It is desirable when the drawer 207 is opened, that the current to the machine shall be cut off. 70 For this reason one terminal of the socket 68 is connected through 222 as shown in Fig. 3, to a contact member 223 secured to the rear wall 224 of the drawer compartment, and the fuse 70 being connected to a mating contact member 225 affixed 75

to the outside of the rear wall 220 of the drawer. The contact members 223 and 225 constitute a switch which is opened on opening the drawer 207 to stop all flow of current to the machine. In order that such flow of current may not be stopped before the machine, including the various solenoids thereof have had full time in which to act, one of the contact members is in the nature of a follower or leaf spring which may be mounted on the conductor block 226 secured to the wall 224. This spring maintains the electrical contact while the opening movement of the drawer is beginning. The length of the spring 223 may be sufficient to afford an adequate margin of time to assure full operation of the machine. When the drawer is closed, this spring is deformed.

The opening of the drawer 207 may be aided by a plurality of expansion helical springs 227 which may be secured to the rear wall 224. A bell 228 having a knocker 229 may be sounded on opening the drawer 207, the latter having a catch 230 to engage, and then to spring the knocker and release the same for sounding the bell.

To regulate the passing of customers before the machine and maintain a proper order in the payment of the checks, a suitable passage closing device may be provided which may directly or indirectly be caused to operate by the machine. For instance the device may operate with the opening and closing of the cash drawer 207. One form of such device may include an arcuate bar 231 which lies in the plane of the base casing section 13 and is adapted to move back and forth therethrough along the arc of the bar as shown in full and dotted lines in Fig. 7. This bar may be of any suitable length or curvature so as to readily pass in front of a person paying his check, and then behind the person when his payment has been made and the drawer closed. The casing section 13 may extend laterally at 13a beyond the drawer casing section 12 so as to afford ample space to accommodate said bar.

The casing section 13 may have openings at 232 and 233 for the passage of the bar. To guide the bar in its oscillation, we provide a plurality of pairs of rollers 234, and additional single rollers 235. The bar 231 may have a rack 236 on its inner surface, the teeth of which mesh with those of a gear 237 which has a fixed bearing at 238, the arrangement being such that the gear is always in engagement with the rack. To actuate the gear 237, a sprocket wheel 239 may be provided on the shaft 238. A chain drive 240 may so connect this sprocket wheel with the drawer 207 as to cause the movement of the latter to operate the bar 231. Thus the chain may engage around the idlers 241, 242, 243 and 244, the idlers 242 and 243 being arranged along a central line of the drawer in the path of movement thereof. For engaging the drawer with the chain 240, a member 245, having a fork 246, is secured to the rear wall 220 of the drawer by longitudinal brackets 247 and may extend downward to closely engage the chain at any part thereof. Thus the chain is detachably reliably engaged by the fork, due to the links of the chain. It will now be seen that when the drawer 207 is opened, the gear 237 is turned in clockwise direction to move the bar 231 to the dotted line position, and when

the drawer is closed, the bar is moved into the position shown in full lines.

To aid the opening movement of the drawer 207 and the movement of the bar 231 into the dotted line position, a rod 248 is mounted on posts 249 at an angle along the path of travel of the chain between the idlers 243 and 244. Secured upon this rod is a slide 250. A tension coil spring 251 takes around the rod and is connected at one end to the slide 250 and at its other end to the end 252 of the rod. The chain 240 may be connected to the slide at 253, at which point a stiff tension coil spring 254 may be interposed in the chain to take up any slack therein. It will now be clear that when the drawer 207 is being opened, the spring 251 facilitates such movement and serves to take up a part of the inertia and friction of the bar 231. When the drawer 207 is closed, an operation that is more easily accomplished than opening the drawer, the spring 251 is elongated.

It will be appreciated that this invention may be embodied in many different forms and constructions, and for different purposes, and that various features and parts of the invention may be changed in whole or in part, or omitted or replaced by others, and that the invention is not to be limited by any construction herein shown, but is rather defined by the following claims.

We claim:

1. A device responsive to perforations successively disposed along a check, including means for releasably holding the check, electrical conductor means, contact elements successively actuated for movement through the perforations to engage said conductor means, and counter means actuated by the first element so moved and continuously during movement of the other elements.

2. A device responsive to amount indicating perforations successively disposed along a check in variably spaced relations to each other, including an electrical conductor means, contact elements uniformly spaced from each other, said conductor means and contact elements being movable relatively to each other so that the contact elements have successive engagement with the conductor means through adjacent perforations, those elements not adjacent to said perforations being maintained by the check out of contact with the conductor means, counting means and means for operating the same, the last mentioned means being actuated by the first element making said engagement and continuously during any succeeding engagement of other elements.

3. A device responsive to perforations successively disposed along a check to indicate increasing amounts, including electrical means comprising circuit and contact elements operative so as to be successively responsive to the perforations, beginning at the perforation representative of the maximum amount, to close the circuit, and means actuated by the electrical means upon closing of the circuit by the first element that responds to a perforation and continuously during operative responses of succeeding elements to succeeding perforations.

PETER ZULINSKI.
